CLOSURE FOR BOTTLES, JARS, AND
THE LIKE

Henry Wiesner, Wheeling, W. Va., assignor to
Hazel-Atlas Glass Company, Wheeling, W. Va.,
a corporation of West Virginia

Application June 22, 1933, Serial No. 677,118

4 Claims. (Cl. 215—43)

The invention relates to metal closures for bottles, jars and the like, and particularly to that type of closure in which there is an inner threaded shell and a smooth outer shell. The general type of closure is shown in the patent to Bernardin No. 653,610, July 10, 1900.

One of the objects of the invention is to improve the appearance of the double shell type of cap. The common practice has been to secure the two shells together by bending the bottom of the skirt of the outer shell inwardly about a portion of the bead on the inner shell. In such constructions the skirt has a tendency to wrinkle as it is turned about the bead, thereby detracting from the appearance of the cap. And further, in such constructions, the raw edge of the skirt remains exposed in its position on the bead, which is undesirable for practical reasons as well as detracting from the appearance of the cap. In accordance with the present invention, the lower portion of the outer skirt is not turned about the bead but is inwardly curled upon itself, so that the bottom of the completed cap presents a perfectly smooth curved surface without any wrinkles and without any exposed raw edge.

Another object of the invention is to provide a closure of this type in which there is no possibility of the inturned portion of the skirt interfering with the proper functioning of the threads on the inner shell. In the constructions in which the skirt is turned inwardly about the bead on the inner shell, the inturned portions may interfere if it is turned too far about the bead. To avoid such interference, where the skirt is turned about the major portion of the bead, it is necessary to form extra deep threads or flare the bottom portion of the inner shell which carries the bead. In accordance with the present invention that is unnecessary, for the in-curved bead on the outer shell is in alignment with the out-curved bead on the inner shell, and hence there is no possibility of interference with the proper functioning of the threads. In other words, the inner shell may be an ordinary standard screw cap.

A further object of the invention is to strengthen closures of this type, by providing two beads.

Still another object of the invention is to provide a secure and permanent fastening between the inner and outer shells, by gripping the two shells by means of the two resilient beads.

Various other objects and advantages of the invention will be apparent to those skilled in the art, from the following detailed description when

taken in connection with the accompanying drawing; in which,

Figure 1 is a perspective view of the completed cap or closure.

Figure 2 is a vertical sectional view of the blank for the outer shell.

Figure 3 is a vertical sectional view of the inner shell arranged in the outer shell; and

Figure 4 is a vertical sectional view of the completed closure.

Referring to the drawing in more detail, numeral 1 indicates the blank for the outer shell, having a top 2 and a depending skirt 3. Numeral 4 refers to a conventional screw cap provided with the usual threads 5, and having an out-curved bead 6 at its lower edge. This conventional screw cap is shown, in Figure 3, assembled with the blank 1, and it will be noted that the skirt of the blank depends below the inner shell, as indicated by numeral 7, a distance sufficient to permit the formation of an in-curved bead.

The conventional screw cap having been assembled in the blank of the outer shell, the formation of the closure is completed by applying a die to the lower edge of the blank. The die will cause the lower portion of the skirt to curl inwardly upon itself to form a bead 7, and by reference to Figure 4 it will be noted that the out-curved bead 6 of the inner shell and the in-curved bead 7 of the outer shell, are in contact.

In the formation of the bead 7 it is jammed tightly against the bead 6, and the resiliency of the two beads provides a firm and permanent gripping action between the two shells, which prevents relative movement between these parts.

In addition to firmly uniting the two shells, the closure of the present invention possesses numerous advantages over the double shell closures now in common use. The inner shell may be an ordinary standard screw cap, without unusually deep threads or without an unusual flare at the bottom. And the blank for the outer shell is an ordinary cylindrical blank. The closure is completed by the mere formation of an in-curved bead on the outer shell, so that the manufacture of the closure of the present invention is very simple and inexpensive. The appearance of the completed closure is improved, for the lower edge presents a perfectly smooth curved surface, without any wrinkles or uneven portions which sometimes appear in the ordinary double shell closures. No raw edges are exposed to view; such raw edges being undesirable for practical reasons as well as detracting from the appearance of the cap. The closure of the present invention is also of much

greater strength than the ordinary double shell closures, by reason of the two beads.

Having fully described the invention, what I claim is:

- 5 1. A closure including an inner shell and an outer shell, each having a top and a depending skirt, the skirt of the inner shell having threads and an out-curved bead at its lower edge, the skirt of the outer shell being smooth throughout and having a complete in-curved bead on its lower edge, the bead on the outer shell being arranged below the bead on the inner shell and the two opposed convex surfaces of the two beads being in resilient abutting relation.
- 10 2. A closure including an inner shell having threads and a bead substantially circular in cross-section, and an outer shell smooth throughout and having a bead substantially circular in cross-section, the second-mentioned bead being below the first-mentioned bead, the two beads being in substantially vertical alignment and the opposed con-
- 15 vex surfaces of the two beads being in resilient abutting relation.
3. A closure including an out-curved conventional screw cap with a bead at its lower edge, a shell having a skirt arranged over the screw cap, said skirt being curled inwardly upon itself to form a complete bead below the first-mentioned bead, the oppositely curved surfaces of the two beads being in resilient engagement.
4. A closure including an inner shell having a skirt and an outer shell having a skirt, threads formed in the inner skirt, an out-curved bead substantially circular in cross-section at the bottom of the inner skirt, an in-curved bead substantially circular in cross-section at the bottom of the outer skirt below the first-mentioned bead, the oppositely curved surfaces of the two beads being in resilient engagement and the inner side of the lower bead being outwardly of said threads.
